C. N. VAN CLEAVE

COIN CONTROLLED LOCK

Filed Mar. 1, 1920

Fig. 1.

INVENTOR,
Charles N. Van Cleave.

BY

Bradford Morrissey Biemus

ATTORNEYS.

UNITED STATES PATENT OFFICE.

CHARLES N. VAN CLEAVE, OF INDIANAPOLIS, INDIANA.

COIN-CONTROLLED LOCK.

Application filed March 1, 1920. Serial No. 362,303.

To all whom it may concern:

Be it known that I, CHARLES N. VAN CLEAVE, a citizen of the United States, residing at Indianapolis, in the county of Marion and State of Indiana, have invented certain new and useful Improvements in Coin-Controlled Locks, of which the following is a specification.

This invention relates to coin controlled locks intended for any purpose which requires a coin to operate a lock and is often employed in public toilets, lockers, baggage receptacles, etc., wherein a locked door is opened by means of a coin. The present invention has among its objects the making of an improved lock which is simple in construction, reliable in operation, and consists of but few parts.

In carrying the objects of my invention into effect, I provide a coin operated lock which is arranged so that upon inserting the proper coin from the outside a connection is formed which allows the backward movement of the bolt on turning the outside knob, at the same time closing the coin slot and unlocking the door. For example, in the case of a toilet door, when the operator enters the room and closes the door behind him the coin drops into the coin box and locks the door which can be opened only from the inside by the occupant of the room. When he leaves the room turning the inside knob the coin slot is uncovered putting the mechanism in operative position again.

Referring to the accompanying drawings forming a part hereof and in which similar reference characters denote similar parts,

Figure 1, illustrates a front view of the lock with the cover and coin box cut away and taken on the line 1—1 of Figure 2, and,

Figure 2, a transverse section taken along line 2—2 of Figure 1.

The casing 1 of the lock has a coin slot 2 in the upper portion thereof communicating with a slotted projection 3 formed on the rear portion of cover 33, and constituting a coin guide. A bolt 4, having a projection 5 and rear extensions 6 and 7, the extension 7 being fitted with spring 8 to hold bolt 4 in closing position, is secured to the casing by guides 9 and 10.

A stop 11 is formed on extension 6 and in proximity thereto is a shaft member 12 having an angular extension 13 upon which

is fitted a knob 14 forming the interior operating handle. Fixed to the inner end of member 12 is a projection 15 adapted to contact with stop 11 and having at its upper end a projection 16. A coin slot cover 17 is journaled in the casing at 18 and has a downwardly extending projection 19 adapted to be engaged by projection 16 and a coin. A forked member 20 is secured to the coin slot cover and engages a pin 21 fixed to counter 22 adapted to record the number of times the lock has been operated.

A shaft 23 is journaled in the casing and has an angular extension 24 with a knob 25 fixed thereto forming the exterior operating handle of the lock. Fixed to this member is a projection 26 having a stop member 27 adapted to engage a projecting stop 28 formed on the casing. A horizontal stop 29 is formed on the casing at a point directly below portion 5 of the bolt which is formed with a coin slot 30 for the reception of a coin 31. The relative sizes of projection 29 and coin slot 30 are such that when the proper coin is inserted it will be held in place by members 29 and 30 with the upper portion of the coin extending in proximity to member 19 and the lower portion to member 26. A coin smaller than the proper size will not be engaged by members 29 and 30 and will drop into the coin box without operating the lock. A coin too large cannot be inserted into coin slot 2. A projection 32 is formed on the upper end of the rear section 33 and has a hollow portion which is adapted to engage a tongue 34 formed on the front part of casing 1 to hold the parts of the casing together.

The operation of the lock is as follows:

In locked position the relative positions of the parts are as shown in the drawings. A coin is inserted in slot 2 and assumes the position shown in Figure 1. This forms connections between stop member 26, the lower portion of the coin, the bolt 4 and projection 19 of coin slot cover 17. Upon turning the knob of exterior operating handle 14 the bolt 4 is shot back and coin slot cover 17 is pushed so as to cover coin slot 2. This allows the toilet door A to be opened and the operator to enter the room whereupon, in closing the door, bolt 4 is again shot back

by contacting with the fixed portion of the latch thereby throwing coin 31 down into the coin box (not shown).

When the occupant leaves the room he 5 turns interior operating handle 14 causing projection 15 to engage stop 11 thus drawing back bolt 4 and causing stop 16 to engage with projection 19 uncovering the coin slot 2. As he closes the door behind him 10 the door is locked and the mechanism is ready for the next occupant. A key 35 is provided so that it may be inserted by an attendant and the lock opened without the use of a coin by engaging stop 16 and pushing 15 it forward causing bolt 4 to be shot back.

Having thus fully described my said invention, what I claim as new and desire to secure by Letters Patent, is:

20 1. A lock for doors and the like comprising a casing having a slot for a coin, a bolt having a slot to receive and hold said coin, a pivoted closure for the slot in the casing, said coin adapted to contact with said closure, and means acting through the coin in the slot of said bolt to retract the bolt and to close the slot in the casing, substantially as set forth.

2. A lock for doors and the like comprising a casing having a slot for a coin, a bolt having a slot to receive and hold said coin, a pivoted closure for the slot in the casing, said coin adapted to contact with said closure, a counting device in said casing, a pivotal connection between said counting device and said closure, and means acting through the coin in the slot of said bolt to retract the bolt to close the slot in the casing and to operate said counting means, substantially as set forth.

3. A coin controlled lock comprising a casing, a bolt, an interior operating handle connected thereto, an exterior operating handle in proximity thereto, a coin slot, 45 means for making connection between said exterior handle and said bolt through a coin, means operated by said coin for closing said coin slot comprising a pivoted coin slot cover in said casing having a projection thereon said coin being adapted to engage said projection, and means on said first han-

dle also adapted to engage projection on said coin slot cover for uncovering said coin slot, substantially as set forth.

4. A coin controlled lock comprising a 55 casing, a bolt, an interior operating handle connected thereto, an exterior operating handle in proximity thereto, a coin slot in said casing, a corresponding coin slot in said bolt transversely thereof, a projection on said casing co-operating with said second slot to hold a coin therein, a projection fixed to said exterior handle adapted to engage the lower portion of said coin for operating said bolt, a pivoted coin slot cover, a projection thereon adapted to engage the upper portion of said coin for closing said coin slot, and means on said interior handle adapted to engage said projection for uncovering said coin slot, substantially as set 70 forth.

5. In a lock, a casing having a coin-slot, a bolt, coin-controlled means to retract the bolt operable from the outer side of the door, a pivoted coin slot cover, a rock shaft, 75 a rock arm thereon engaging the bolt, a second rock arm on said rock shaft adapted to retract the cover, and means at the inner side of the door whereby the rock shaft may be operated to retract the bolt said second 80 rock arm being actuated by a key for turning the rock shaft to retract the bolt, substantially as set forth.

6. In a lock, a casing having a coin slot, a bolt having a transverse slot for passage 85 of a coin, an exterior handle, a rock shaft therefor having an arm to bear against the coin, a ledge adjacent the bolt adapted to hold in the slot only coins of a predetermined size and having a stop forming a 90 guide for the coin, and an arm on said rock shaft arranged to abut against said stop to limit the movement of the rock shaft, substantially as set forth.

In witness whereof, I have hereunto set 95 my hand at Indianapolis, Indiana, this 24th day of February, A. D. nineteen hundred and twenty.

CHARLES N. VAN CLEAVE.
